UNITED STATES PATENT OFFICE.

VERNON ROYLE, OF PATERSON, NEW JERSEY.

CIRCULAR LOOM.

1,115,338.

Specification of Letters Patent. Patented Oct. 27, 1914.

Application filed December 15, 1911. Serial No. 665,991.

To all whom it may concern:

Be it known that I, VERNON ROYLE, a citizen of the United States, and resident of Paterson, in the county of Passaic and State 5 of New Jersey, have invented a new and useful Circular Loom, of which the following is a specification.

My invention relates to a circular loom and more particularly to a circular loom of 10 the general type shown, described and claimed in Letters Patent No. 795228, granted to A. de Laski, July 18, 1905.

The objects are to improve the construction of the parts at the "weaving point"; 15 to improve the structure and arrangement of the tension and evening rolls; to provide for the adjustment of the weaving pin and the removal of the weaving pin and its guiding and adjusting mechanisms; to improve 20 the shuttle and mechanism coacting therewith; to improve the structure and arrangement of the take-off rolls and to provide means for directing the warp threads at equal intervals to the "weaving point", simplify and render more effective the "take-up" mechanism, provide for the effective 25 manipulation of the heddles and to simplify the structure of the revolving parts of the loom, to provide for gaining ready access to 30 the interior parts without disturbing the loom frame, and, in general, increase the capacity and efficiency of the loom as a whole.

My invention further contemplates certain features of construction and combination of parts as will be hereinafter described 35 and pointed out in the claims.

In the accompanying drawings, Figure 1 is a vertical central section of the loom, Fig. 2 is a top plan view partly broken away 40 omitting the driving mechanism, take-up and warp tension and evening rolls, Fig. 3 is a horizontal section in the plane of the line A—A of Fig. 1, Fig. 4 is a horizontal section in the plane of the line B—B of Fig. 1, Fig. 5 is a horizontal section in the plane of the line C—C of Fig. 1, Fig. 6 is an enlarged partial vertical central section, Fig. 7 is an enlarged partial horizontal section in the plane in which Fig. 3 is taken, Fig. 8 45 shows in detail a longitudinal section of the tension roll, Fig. 9 is a transverse section of the same in the plane of the line D—D of Fig. 8, Fig. 10 is a view in detail in elevation of a portion of the heddles and heddle 50 manipulating mechanism, Fig. 11 is a top plan view of the same, Fig. 12 is a section of 55

the same in the plane of the line E—E of Fig. 10, Fig. 13 is a section in the plane of the line F—F of Fig. 12, Fig. 14 is a view in detail of the worm and shaft for adjusting the weaving pin, Figs. 15, 16 and 17 are front, edge and rear elevations of a heddle, Fig. 18 is a sectional view in detail of the reversing gear, Fig. 19 is a top plan view in detail partly broken away of a shuttle, Fig. 60 20 is an edge view of the same, Fig. 21 is a transverse section in the plane of the line G—G of Fig. 19, Fig. 22 is a transverse section in the plane of the line H—H of Fig. 19, with cop holder removed, Fig. 23 is a 65 transverse section in the plane of the line I—I of Fig. 19, Fig. 24 is a top plan view in detail of the weft lays, Fig. 25 is a section in the plane of the line K—K of Fig. 24, Fig. 26 is a transverse section in the plane of the line L—L of Fig. 24, Fig. 27 is a top 70 plan view of weft lays, for weaving a tube of small diameter, Fig. 28 is a section in the plane of the line M—M of Fig. 27, Fig. 29 is a transverse section in the plane of the line N—N of Fig. 27, Figs. 30, 31 and 32, represent one of the shuttle driving shafts with pinions thereon, in elevation, assembled in section, and in elevation unassembled, Figs. 33 to 43 inclusive, show different 75 positions of the parts at the point of weaving during the passage of the shuttle along a given point on the periphery of the weaving pin, Fig. 44 is a view in elevation in detail showing a means for locking the heddle-frame ways against displacement, and Fig. 45 shows a plan view of the locking device. 80 85 90

The frame comprises a base 1 from which pillars 2, in the present instance eight in number, uprise and support a table 3. From the table 3 smaller pillars 4 uprise and support a cap plate 5. The number of pillars 4 is, in the present instance, sixteen, located at equal distances apart. The pillars 2 also support an intermediate annular table 6 on 95 which heddle operating slides are located as will hereinafter appear.

The table 3 has seated thereon a central table 7 provided with a hub 8 connected with the rim by arms 9. The table 7 has a marginal flange 10 which overlaps the inner edge of the table 3 while the periphery of said central table below the marginal flange fits within the table 3 holding the table 7 100 centered and permitting its removal upward without disturbing the pillars 2 and 110 4 and table 3.

Centrally in the base 1 there is an opening 11 around the margin of which an inverted cup-plate 12 is secured, a tubular part 13 extending upwardly from the top of the cup plate. Around the crown of the cup plate there is a flange 14 to arrest dripping oil or grease and at the top of the tubular part 13 there is a bearing flange 15. A tubular foot piece 16 fits within the tubular part 13 and a supporting flange 17 on said tubular foot piece rests on the bearing flange 15. A cam wheel 18, for operating the heddles, has its hollow hub 19 bolted to the top of the foot piece 16, and to the top of the hub 19 the hub 20 of the master gear wheel 21 is bolted, the said hub 20 being provided with an upward tubular extension 22 which enters with a rotary fit the hub of the central table 7. The several moving parts superposed as above described, are so formed that, when assembled, their interior bores will form a continuous bore with substantially uninterrupted wall.

Weaving pin.—The weaving pin is denoted by 23. It is here shown as a circular cup, the base of which is provided with a screw threaded hole to receive the upper end of a supporting rod 24, the latter being provided with a screw threaded portion 25 to screw into the base of the pin, and with a collar 26 in position to engage the bottom of the pin when the rod is screwed in to its limit. The rod is centered by passing through the hub 27 of a spider 28 seated on an interior shoulder 29 in the hub of the master wheel 21 and extends thence downwardly to a point within the cup 12 where it is provided with a rack 30, removably secured to the rod by means of a split sleeve 31 and screw 32. A horizontal shaft 33, mounted in suitable bearings on the base 1 and in the cup plate 12, has, on its inner end, a pinion 34, held in engagement with the rack 30 by a shoe 35, provided with per-

40 forated ears 36, 37, through which the shaft 33 extends. The rack 30 is free to slide up and down in the shoe 35. The outer end of the shaft 33 is provided with a worm wheel 38, engaged with a worm 39 (see Fig. 14) on an upright shaft 40, the latter having a hand wheel 41 secured to its upper end for manipulating it and hence through the worm 39, worm wheel 38, pinion 34 and rack 30, adjusting the weaving pin 23 up and down at pleasure during the operation of the machine or when the latter is at rest. The shaft 40 also serves as a way for the heddle frame to slide on and occupies a position corresponding to one of the fixed ways to be hereinafter described.

The shaft 33 is held against longitudinal displacement by a screw pin 42 passing through the bearing on the base and into an annular groove (not shown) on the shaft 33. To permit the shaft 33 to be withdrawn

from within the cup plate 12 to free the interior of the bore, formed by the superposed parts 16, 19 and 22, from obstruction when the loom is used for covering hose, the lower end of the shaft 40 is held in position by a hook 43 formed on the shaft bearing and by a swinging hook 44 removably clamped to the said bearing by a set screw 45. By releasing the hook 44 the lower end of the shaft 40 may be moved away from the worm wheel 38 sufficient to disengage the worm from the wheel and then by unscrewing the pin 42 the shaft 33 with worm wheel thereon may be drawn outwardly from within the cup plate 12 and at the same time from the ears 36, 37, on the shoe 35, releasing the shoe and permitting it and the shaft 24, spider 28 and weaving pin 23 to be removed.

On the upper end of the hub 8 of the center plate 7, an interiorly screw threaded collar 46 is secured and a hollow nut 47 is fitted to screw into the collar 46. A ring 48 performing the double function of a weft lay or weft guide support and a centering guide for the weaving pin is seated on an annular interior shoulder 49 within the nut 47. The upper edge of the ring 48 is transversely corrugated as shown at 50 for preventing lateral displacement of the warp threads during the operation of weaving as will hereinafter appear. By screwing the nut 47 up or down the weft lay support carried by the nut may be accurately adjusted with relation to the weft lay carried by the shuttle.

Shuttle.—Two shuttles are employed arranged to travel tandem and quite like one another in structure and operation. A description of one will suffice. The shuttle frame is denoted by 51. It is of skeleton formation and has two supporting wheels 52, 53, which track one after the other along an annular track 54, faced with raw hide or other suitable noise reducing material. The frame 51 also has journaled therein three pairs of guide wheels 55, 56, 57, on upright journals, the upper wheel of each pair engaging the inner wall of an upper comb 58, and the lower wheel of each pair engaging the inner wall of a lower comb 59. The said shuttle frame has also journaled therein on upright journals two pairs of guide wheels 60, 61, the upper wheel of each pair engaging the outer wall of the said upper comb and the lower wheel of each pair engaging the outer wall of the said lower comb. The said guide wheels are preferably made of raw hide or other suitable noise reducing material.

The upper comb 58 is curved to conform to the track 54 and is fixed to a plate 62 supported by and removable from an annular plate 63 carried by the pillars 4, and the lower comb 59 is similarly curved and fixed to the center plate 7. These combs or

“picket fences” are located one above the other with their teeth directed toward one another and spaced apart to permit the frame 51 of the shuttle to pass between them 5 and the slits 64 which separate the teeth are given such a slant relative to the edge of the comb, where necessary, that the ends of the slits at the bases of the teeth, where the warp threads are located when the shuttle passes, 10 are equidistant throughout the entire circuit of weaving, while the ends of the teeth are so located and formed that the warp threads will be properly engaged and separately guided to the ends of the slits.

15 The back or outer edge of the shuttle is provided with a curved rack 65 for engaging the shuttle driving pinions to be herein-after described. A broad upright bearing rim 66 on the shuttle frame above the rack 20 65 engages rollers on the driving pinion shafts to hold the rack and pinions in proper mesh to prevent both cramping and lost motion. The rollers above referred to will be more particularly described in connection 25 with the drive mechanism.

The weft lay or guide carried by the shuttle consists of an arc-shaped piece 67 (see Figs. 24 to 28) provided on its face with a spiral groove 68 along which the weft thread 30 is guided, the pitch of the spiral groove being preferably equal to the diameter of a thread from the point where the thread enters the groove to the point where it leaves the groove, so that the weft threads, during 35 the passage of the shuttle along a given point on the weaving pin will screw the thread snugly against the previously laid thread. The entering end of the weft lay or guide is turned slightly to one side of 40 center as shown at 69, to insure the entrance of the lay or guide between the two sets of warp and the trailing end of said lay or guide is cut away as shown at 70 to free the weft thread being laid from any obstruction 45 between it and the previously laid weft thread as the lay finally forces its thread into position. The lay or guide 67 has a curve properly related to the curve of the weaving pin, and as the latter is changed in 50 diameter, the lay or guide is replaced by another to suit the conditions.

Figs. 27 to 29 show a lay or guide 71, suited to a weaving pin of smaller diameter than the pin to which the lay or guide 67 is 55 suited but in other respects the lay or guide 71 is quite similar to the lay or guide 67. The lay or guide is removably secured to a curved holder 72, the face of the holder being provided with a groove 73 for receiving 60 a pin 74 on the back of the lay or guide and screws 75 extending through the holder and into screw threaded sockets tapped into the back of the lay. The holder 72 is further provided with laterally extending 65 flanges 76, 77, which gradually increase in

width from the advance end of the holder toward its middle portion and then gradually decrease in width toward its trailing end. The advance end of the holder is constructed to enter between the two sets of 70 warp threads before the advance end of the guide enters and serves to spread the said sets to receive the lay, and the trailing end of the holder is constructed to pass from between the sets of warp before the trailing 75 end of the lay passes to allow the sets of warp to begin their change of positions under the action of the heddles at the earliest feasible moment ready for the following shuttle. Where the lay is made for weaving 80 tubular fabric of smaller diameter, the advance end of the holder may be given an outward curve, as shown at 78 (Fig. 27) to cause its flanges to spread the sets of warp more abruptly with respect to the advance 85 end of the lay. The holder 72 is removably secured to the shuttle frame by means of arms 79, 80, bolted to projections 81, 82, on the frame and to admit of accurate adjustment the holes 83 through which the 90 bolts 84 pass are elongated. The holder is further provided with a guide pulley 85, around which the weft thread from the cop passes to a hole 86 communicating with the groove in the lay, near its advance end. 95 The said lay or guide coats with the support 48, hereinbefore described, the said support serving to prevent the lay from being crowded away from the edge of the fabric being woven and hence causing the 100 weft thread being laid to be gradually forced by the spiral incline, tightly against the previously laid weft thread.

The cop holder is denoted by 87 and consists of a hollow cylinder for receiving the 105 cop, one end 88 (see Fig. 21) being hinged at 89 to swing open, the said end being provided with a thread hole 90. A rod or tube 91, provided with a thread passage 92, leading from the end of the rod or tube through 110 the side of the tube, is spaced from, and attached to the body 87 of the cop holder by means of bands or clips 93, 94, around the ends of the said body. The rod or tube 91 is employed to apply tension to the weft 115 and is provided with a scale 95 to determine its rotary adjustment. A nut 96 on the end of the rod or tube 91 serves to hold it in the desired adjustment.

The side of the holder 87, preferably opposite the tension rod or tube 91, is provided with a dovetail tongue 97, the lower edge of which seats in a fixed jaw 98 on the shuttle frame, and the upper edge of which is embraced by the jaws 99 of two clamping plates 100, 101, the opposite edges of said plates being provided with downward projections 102 adapted to enter depressions 103 in the shuttle frame. Bolts 104, 105, 120 extending upwardly through the frame and 130

through the clamping plates 100, 101, serve to lock the plates and hence the cop holder securely to the frame while permitting its ready bodily removal from the frame by 5 simply loosening the bolts 104, 105.

Warp spreaders are carried by the shuttle, a main spreader denoted by 106, extending substantially the length of the shuttle and connecting at its opposite ends with auxiliary spreaders 107, 108. These auxiliary spreaders coat with a spreader 109 carried by the cop holder and removable with the cop holder thereby affording free access to the shuttle for manipulating the cop holder. 10 and, at the same time, maintaining a continuous spreading of the warp threads, the adjacent ends of the auxiliary and cop holder supported spreaders being so overlapped as to form no break in the spreading action. It is to be understood that spreaders corresponding to those noted on the upper side of the shuttle are provided on the under side of the shuttle. 15

Heddles.—The heddles are arranged in 20 banks, in the present instance sixteen banks, each bank comprising an outer and inner element, the outer element handling one set of warp threads and the inner element its companion set of warp threads which make 25 up a shed, sixteen sheds being employed to distribute the warp around the complete periphery of the weaving pin. It is to be understood, however, that the number of sheds of warp is a matter of choice and I 30 do not wish to limit myself to a particular number. The heddle frame of an element comprises side rods 110, 111, and end slats 112, 113, the ends of which are let into slots 114, 115, in the ends of the side rods, it being 35 understood that the lower end of the side rod 110, is provided with a slot corresponding to the slot 114 and the lower end of the side rod 111 with a slot corresponding to the slot 115, to receive the ends of the bottom end slat 113. One of the heddles is 40 shown in detail in Figs. 15, 16, 17, and consists of a flat strip of metal 116 provided with slots 117, 118, near its opposite ends and at its middle portion with a clip 119. 45 struck up from the body of the strip and serving with the portions of the strip on the opposite sides of the clip to retain a thread eye 120, through which the warp thread passes. The heddle bars 121, 122, pass 50 through the slots 117, 118, respectively, and enter slots in the side rods 110, 111, the slots which receive the ends of the heddle bar 121 being elongated as shown at 123 (Fig. 12) to admit of forcing the bar 121 55 away from the bar 122, to hold the heddles extended. For this purpose the side rods 110 and 111 are provided with screw threads 124, 125, and nuts 126 and 127 are located on said threaded portions below the bar 121 60 and in engagement with the bar. The nuts 65

126 and 127 are provided with suitable lock nuts to hold them in position. At the corners of the heddle frame, half bearings 128, 129, 130, and 131, are riveted at two corners on one side and bolted at the other two corners 70 in order that the frame may be readily taken from the ways. The ways with which the half bearings engage and on which the heddle frame slides up and down, are denoted by 132, 133, and are held in brackets 75 134, 135, supported on the pillars 4. In like manner each element of each of the banks of heddles is constructed and arranged.

For each bank of heddles there is a heddle operating slide 136 provided with a pin 137 80 carrying an anti-friction roller 138 which enters the cam groove in the cam 18. The slide 136 is suitably housed in longitudinally sliding adjustment and has a rack 139 at its outer end, with which a pinion 140 is held 85 in engagement by a cup bracket 141, in which the pinion is mounted, the said bracket being bolted to the housing of the slide 136 on the table 6. The shaft of the pinion 140 has fixed thereon oppositely extending arms 142, 143, one, connected by a link 144 with one heddle frame of a bank and the other connected by a link 145 with the other heddle frame of a bank. The cam 18 is so shaped that it will promptly operate the slide 136 at each of two equidistant points throughout its length during a single rotation of the cam and these points are so related to the positions of the two shuttles that the slide and hence the two sets of 100 heddles of a bank will be operated between the passing of one shuttle and the approach of the other shuttle. In like manner each bank of heddles will be successively operated during the rotary movement of the cam 18. 105

Warp tension and evening rolls.—Around the base 1 there is a roller supporting frame 146 in the form of a mutilated ring, a short portion which extends along the neck of the base 1 where the loom driving mechanism is located being thrown out of the fair line of the ring. The frame 146 is removably secured to the base 1 by any suitable means, in the present instance by means of several pins 147 (see Fig. 5) which enter sockets 148 in the ring frame 146 and sockets 149 in the base, the said pins being held in place by set screws 150 and 151, and further by bolts 152, 153, passing through lugs on the ring frame into the neck of the base. The 110 frame 146 is provided at suitable intervals throughout its length with outwardly directed supporting arms arranged in pairs, the members of a pair being denoted by 154, 155, and between two arms, one of each pair, a warp evening roll 156, is located, journaled in the arms. In the present instance, there are sixteen of these warp evening rolls, the term "evening" being applied to indicate their function in evenly distributing the 115 120 125 130 135 140 145 150 155 160 165 170 175 180 185 190 195 200

tension throughout the entire circuit of warp sheds. The rolls 156 are interconnected by intermeshing gears, two such gears being indicated by 157, 158, so that they move together as though they were one. Certain of these warp evening rolls, in the present instance two, adjacent to one another, are so constructed that they can be released from their companion rolls, at the pleasure of the operator, to permit them to rotate without disturbing the gears which connect them to their companion rolls. The two special rolls referred to are denoted by 156*, being duplicates of each other and each having a pair of hubs 159, 160, independent of the regular roll hubs 161, the latter loosely mounted on the roll shaft 162 and fixed to the body of the roll, while the hubs 159, 160, are screw-threaded on the shaft 162 and also arranged that they may be screwed toward the opposite ends of the roll to lock it to the shaft 162, or screwed away from the opposite ends of the roll to release it and permit it to rotate on the shaft. These special rolls are located in proximity to the tension roll to be hereinafter described, and serve to enable the operator to gain access to the tension roll by releasing the rolls 156* and then drawing off sufficient lengths of warp to permit the warp from the rolls 156* to be pushed aside. After the occasion for so pushing aside the warp has passed the said rolls 156* may be turned by hand to take the drawn off warp back again and then by locking the rolls 156* to their shafts the operation of weaving may proceed, the relative positions of the evening rolls remaining unchanged.

The tension roll, denoted as a whole by 163, is shown in its relation to the evening rolls in Fig. 1 and in detail in Figs. 8 and 9. It is mounted in a two-armed bracket 164 fastened to the ring frame 146, and carries a gear wheel 165 which meshes with a gear 166 on the shaft of one of the evening rolls 156*. The said tension roll consists of a cylindrical shell 167, secured between two flanged end hubs 168, 169, the flanges on said hubs serving as supports for a series of rods 170, in the present instance six, at equal distances apart. The rods 170 support a series of ring-like, flat-faced disks 171, having their opposite faces within the fair path of the rods 170 provided with suitable friction material 172. The flanged hub 168, carries the gear 165 and the two hubs 168, 169, are mounted respectively on drums 173, 174, made fast in the arms of the two-armed bracket 164. The drums 173, 174, are provided with outward extending flanges 175, 176, at their outer ends, through which they are secured to the arms of the bracket and with inwardly extending flanges 177, 178, at their inner ends, through which flanges 65 pass a series of rods 179, in the present in-

stance eight, at equal distances apart. On the rods 179, two end caps 180, 181, and a series of disks 182 are mounted, the disks 182 extending outwardly between the friction material on the faces of two adjacent disks 171 and the end caps 180, 181, engaging the friction material on the outer faces of the disks 171 at the opposite ends of the series. The rods 179 are within the ring disks 171 so that the latter may rotate without interfering with them. The disks 182 are open at the center to admit inwardly projecting spring-retaining pressure cups 183, 184. The said cups are provided with annular shoulders 185, 186, which bear respectively against the cap plates 180, 181, and at their outer ends with flanges 187, 188, which are fitted to slide within the drums 173, 174. Coiled springs 189, 190, are seated respectively in the cups 183, 184, their inner ends bearing against the bottoms of the cups and their outer ends against plates 191, 192, which are fitted to slide in the outer ends of the drums 173, 174. Pins 193, 194, pass through the plates 191, 192, and flanges 187, 188, and are made fast in the flanges 177, 178, of the drum to hold the said plates and spring retaining cups against rotation relative to the drums, while permitting the said plates and cups to slide within the drums. An adjusting rod 195 extends centrally through the plates 191, 192, and through the bottoms of the cups 183, 184, the outer ends of the rod being screw threaded to receive adjusting nuts 196, 197, exterior to the plates 191, 192. The said adjusting rod is further provided with a collar 198 against which the inner face of the plate 191 bears, and a pin 199, fixed in the plate 191 extends along a groove in the collar 198 to prevent the rod 195 from rotating relatively to the plate 191.

In operation, the plate 191 having been adjusted against the collar 198 and the nut 196 screwed on against the outer face of the plate, the desired tension may be applied to the rotary cylindrical shell 167 and its gear 165 by turning on the nut 197, thereby drawing the plates 191, 192, toward each other and, through the medium of the springs 189, 190, pressing the cups 183, 184, toward each other and hence the end caps 180, 181, and the disks between them into closer frictional contact. Whatever tension is so applied will be communicated through the gears 165, and 166, to the evening rolls and hence to the threads passing around them. Tension may be relieved at any time by simply unscrewing the nut 196 and the exact former tension restored by screwing the nut 196 on until the plate 191 bears against the collar 198, the nut 197 remaining undisturbed.

Take-up mechanism.—Each shed of warp passes from an evening roll over a guide roll 200 mounted in suitable bearings in a

bracket 201 secured to and projecting outwardly from the pillars 4, the same bracket forming a support for the heddle guides 132, 133, heretofore referred to. The threads 5 as they extend upward from the evening rolls are separated by the fingers 202 on a bar 203 carried at the lower part of the bracket 201 and thence each thread passes in front of a series of bars 204 the present 10 instance four bars, and through loops or eyes 205 interposed between the bars 204 and attached to a swinging arm 206 mounted on a rod 207 carried by the bracket 201. The arms 206, one for each thread, work independently of one another, and each is 15 under the tension of a spring 208, attached at one end to the arm and at the opposite end to a rod 209 held in arms 210 depending from a sleeve 211 mounted on a rod 212 carried by the bracket 201. The sleeve 211 is held in the desired rocked adjustment on the rod 212 by a set screw 213, to give the proper tension to the spring 208 to draw the take-up arm 206 back whenever the thread 20 slackens, as during the crossing of the warps at each pick. If a warp thread breaks, the arm 206 is rocked back against a stop rod 214 as shown in dotted lines Fig. 6. By multiplying the number of bars 204 and 25 alternating loops or eyes 205, the slack is promptly taken up by a slight movement of the take-up arm and the thread is moved but little out of its normal course at any one point.

35 *Take-off rolls.*—The take-off rolls 215, 216 (see Figs. 1 and 2) are mounted in hangers depending from rock shafts 217, 218, mounted in the ends of a housing 219 at the middle portion of a bracket 220 removably bolted to the cap plate 5. One pair of these hangers denoted by 221, 222, is shown in Fig. 1, and it is to be understood that a pair of similar hangers depend from the shaft 218 to support the roll 216. One of 40 the rolls, in the present instance the roll 215, is mounted in yielding bearings 223, 224, of any suitable construction, to permit it to move away from its companion rolls in the event of any slight abnormal increase in the 45 thickness of the woven tube. The rock shafts 217, 218, have inter-engaging toothed sectors 225, 226, fixed thereon so that the rocking movement of one shaft will be communicated to the other and cause the rolls 50 215, 216, to simultaneously move toward or away from each other depending upon the direction in which the shaft is rocked. A spring lever 227 is attached at one end to the shaft 218 and near its opposite, or 55 handle end, it engages in some one of a series of notches 228 or 229 to hold it and hence the take-off rolls in the desired adjustment toward or away from each other.

60 The rolls 215, 216, are positively driven by means of shafts 230, 231, provided with

the usual universal couplings and with worm wheels 232, 233, engaged by a worm 234 on an upright shaft 235, which shaft is provided with a hand wheel 236 and is adapted to be connected with the driving mechanism, 70 by a sliding clutch 237 operated by a handle 238 pivoted on a bracket 239 and connected with the clutch by a connecting rod 240. The bracket 239 is attached to the cap plate 5 and supports the shafts 230, 231, and 75 guides the upright shaft 235.

The driving mechanism.—The loom frame is fitted to receive a suitable support for an electric motor 241 which transmits its power through a belt 242 to a pulley 243 on the 80 outer end of a main drive shaft 244. The shaft 244 is mounted in suitable bearings in a bar frame 245 secured on the base 1. A bracket 246 is removably secured to the outer face of the box frame 245 to form a 85 rest for the lower ends of two outer standards 247, 248, and two shorter inner standards 249, 250, rest on the cap plate 5. These standards are connected by head frame 251 on which the motor frame is secured. In the 90 event some other source of power other than electric is to be employed, the standards and their head frame and supporting bracket may be removed and a driving belt may be led from such other source of power to the 95 pulley 243. The loom is thus adapted to use in connection with water, steam, electric or other power, without disturbing its integrity.

The main drive shaft 244 carries on its 100 inner end a bevel gear wheel 252, which intermeshes with a bevel gear wheel 253, on an upright shaft 254, stepped in a bearing 255 on the box frame 245. The upper end of the shaft 254 is mounted in a suitable bearing 105 in the table 3 and said shaft has a driving pinion 256 fixed thereon which intermeshes with the master gear wheel 21 hereinbefore referred to. This affords a direct drive from the upright shaft, to the master gear which 110 in turn directly engages pinions 257 on the several upright shuttle driving spindles 258. These shuttle driving spindles are each provided with a drive pinion 259 which engages the rack 65 carried by the shuttle. The said 115 spindles are also each provided with a roller 260, immediately above the drive pinion, in position to bear against the broad rim 66 on the shuttle, hereinbefore referred to. The rollers 260 are made of rawhide or other 120 suitable noise reducing material and roll on the spindle independently of the pinions to prevent any drag which would result from the bearing face of the rim 66 being out of the pitch line of the intermeshing gears 65 and 259.

The spindles 258 on which the pinions 257 and 259 are carried, consist of round rods to which the hubs of the pinions are locked by means of keys having heads 257* for 130

interlocking with the hubs of the pinions (see Figs. 30, 31, 32,) and shanks 258* for seating in flat bottomed recesses 259* in the wall of the spindle, the said shanks having a slight taper to produce a wedging action between the inner wall of the hub of the pinion and the shank, the pinion serving to hold the key in position and the key serving to lock the pinion to the spindle.

To arrange for reversing the drive shaft to weave in opposite directions without changing the direction of movement of the take-off rollers 215, 216, as when weaving a covering on hose, in the direction reverse to that in which a previously applied covering was woven, the drive shaft 244 (see Figs. 1, 6 and 18) is provided within the box frame 252 with a sleeve 261, keyed to rotate with the shaft but permitted to slide endwise thereon. The sleeve 261 has fixed thereon two bevel gear pinions 262, 263, either of which may be brought into mesh with a bevel gear wheel 264 mounted in a suitable bearing 265 on the box frame. The said pinions are so spaced that by a short movement of the sleeve 261 in one direction the pinion 262 may be brought into mesh with the gear wheel 264 on one side and the other pinion 263 thrown out of mesh at the opposite side and by a similar movement in the opposite direction the pinion 263 may be brought into mesh with the gear wheel 264 at the opposite side and the other pinion thereon out of mesh. The sleeve 261 is held in either of its two positions by a pair of arms 266, 267, branching from a stem 268 after the manner of a belt shifter, the ends of the arms entering an annular groove 269, in the periphery of the sleeve. The stem 268 projects from a plate 270 bolted to the side of the box frame over an opening 271. In order to utilize a single set of bolts to hold the sleeve retaining arms 266, 267, in position to locate the sleeve in either of its adjusted positions, the stem 268 and arms are off-set in the direction of the axis of the drive shaft, from the axis of the gear wheel 264 as plainly shown in Figs. 1 and 6, so that by reversing the plate 270 to bring its upper edge downward the off-set of the arms 266, 267, will be changed from one side of the center of the gear wheel 264 to the opposite side, the off-set being so calculated as to hold the sleeve 261 and pinions thereon in either of the two operative positions. The shaft of the gear wheel 264 is provided with a pinion 272 which engages an intermediate gear wheel 273, the shaft of which is mounted in a sliding bearing 274, adjustably secured in an elongated slot 275 in an arm 276 clamped in the desired rotary adjustment to the exterior of the bearing 265 by means of a split sleeve 277 and bolt 278. The shaft of the intermediate gear wheel 273 is provided with

a pinion 278* which engages a gear wheel 279 on a shaft 280 mounted in the top of the box frame 255 and carrying on its end opposite that on which the gear wheel 279 is secured, a bevel pinion 281 which engages a bevel gear wheel 282 loosely mounted at the lower end of the worm shaft 235 hereinbefore referred to, and adapted to be locked to and released from the shaft 235 by the clutch 237.

The operator may release the take-off rolls from the driving mechanism at pleasure by lifting the clutch 237 out of engagement with the hub of the gear wheel 282 and may then manipulate the said rolls in either direction by turning the hand wheel 236.

In Figs. 44 and 45 means are shown for locking the heddle frame ways 132, 133, against any possible displacement by jarring down under the vibrations during the operation of the loom. The ways are each provided with a recess 287, and when both the ways in a single bracket 134 are to be locked, as in all instances except where the way is utilized to perform an additional function as the way and shaft 40, a single piece of spring metal 288 slightly arched, as shown, may be arranged to have its ends enter the recesses 287 in adjacent ways and by a set screw 289 passing through the lock latch 95 and tapped into the bracket, the said lock-latch may be sprung downwardly at the middle portion, thereby crowding the ways laterally against the walls of their sockets, thus positively preventing downward displacement and taking up all lost motion.

Operation.—The functions and operations of the several parts have been so fully described that an extended recital of the operations as a whole is deemed unnecessary. The operation at the weaving point, one of the most important features of the present invention, may, however, be emphasized by reference to the series of illustrations, Figs. 33 to 43 inclusive. Fig. 33 shows the upper and lower threads, denoted, respectively, by 283, 284, in the position which they assume when the heddles have just passed the centers of their reciprocatory movements, and the advance end of the shuttle is about to enter the shed. In Fig. 34 the advance end of the lay holder 72 is shown entering the shed. In Fig. 35 the advance end of the lay holder 72 has entered the shed spreading the upper and lower sets of warp near the weaving pin 23 and the advance end of the lay is just entering between the two sets of threads. Figs. 36 and 37 represent the action of the lay at short successive steps previous to the introduction of the weft thread, showing the pushing back of the threads 283 and lifting of the threads 284 in order to lay the weft thread as close as may be to the previous weft thread at the beginning. In Fig. 38, the weft thread 286 has been 130

laid and the action of screwing it up toward the previously laid weft thread has begun. This action is shown progressively in the following figures, 39, 40, 41, 42, the lay holder vanishing as the trailing end of the lay completes its work and in Fig. 43 the threads have been again crossed for the reception of the following shuttle and a repetition of the operation hereinabove described.

The sets of warp threads alternately passing between the lay and the ring support and thence between the face of the lay and the core are subjected to tension, which, for certain purposes, is quite sufficient without the evening rolls and when so used the evening rolls and their supporting ring may be bodily removed from the loom frame.

As the weaving may take place either about a ring or weaving pin, as in weaving a tubular hose, or about a hose or wire, as in weaving a hose covering or insulating a wire, I have chosen the word "core" to cover generically all these forms about which the weaving may take place.

What I claim is:—

1. In a circular loom, the combination with means for manipulating the warp threads, a core about which the weaving takes place and means for directing a weft thread into operative relation to the warp threads at the periphery of the core, of a traveling wedge in position to force the weft thread against a previously laid weft thread.
2. In a circular loom, the combination with means for manipulating the warp threads, of means for simultaneously laying a weft thread and forcing it toward a previously laid weft thread.
3. In a circular loom, the combination with means for manipulating the warp threads, of an inclined plane for simultaneously laying a weft thread and forcing it toward a previously laid weft thread.
4. In a circular loom, the combination with means for manipulating the warp threads, of a lay provided with a spiral groove for guiding the weft thread and screwing it toward a previously laid weft thread.
5. In a circular loom, the combination with means for manipulating the warp threads, of a lay provided with a groove for guiding a weft thread, a wall gradually diminishing in thickness from the advance toward the trailing end of the groove on the side toward a previously laid weft thread, a wall gradually increasing in thickness from the advance toward the trailing end of the groove on the opposite side of the groove and means for holding the lay against movement in a direction away from the previously laid weft thread.
6. In a circular loom, the combination with a core about which the weaving takes place

and means for manipulating the warp threads, of a lay having a face made to conform to the surface of the core and provided with a spiral groove along the face for guiding a weft thread and a lay support surrounding the core for holding the lay to its work.

7. In a circular loom, the combination with a core about which the weaving takes place and means for manipulating the warp threads, of a lay for guiding a weft thread into position in proximity to the core and a lay support for preventing the lay from moving in a direction along the core away from the previously laid weft thread.

8. In a circular loom, the combination with a core about which the weaving takes place and means for manipulating the warp threads, of a lay for guiding a weft thread into position in proximity to the core and an adjustable lay support for preventing the lay from moving along the core in a direction away from the previously laid weft thread.

9. In a circular loom, the combination with a core about which the weaving takes place and means for manipulating the warp threads, of a lay for guiding a weft thread into position in proximity to the core, a lay support holder and a lay support having a screw threaded engagement with its holder for adjusting the support along the core.

10. In a circular loom, the combination with means for manipulating the warp threads, of a lay provided with an inclined groove on its face for guiding a weft thread into position and with a passageway through the back of the lay leading to the groove for directing a weft thread into the groove.

11. In a circular loom, the combination with means for manipulating the warp threads, of a lay for guiding a weft thread into position, a lay holder, the lay and its holder being provided the one with a tongue and the other with a groove to receive the tongue and means for locking the lay to its holder.

12. In a circular loom, the combination with means for manipulating the warp threads, of a lay for guiding a weft thread into position, and a lay holder having its forward end in advance of the forward end of the lay and provided with warp spreaders for opening the sets of warp threads for the entrance of the lay.

13. In a circular loom, the combination with means for manipulating the warp threads, of an arc shaped lay for guiding a weft thread into position and a lay holder having the same general curve of the lay but having its forward end turned outward from the general curve and provided with warp spreaders for opening the sets of warp in advance of the lay.

14. In a circular loom, the combination with means for manipulating the warp threads, of a lay for guiding a weft thread into position and a lay holder provided with means for opening the sets of warp in advance of the lay, the forward end of the lay being turned toward the previously laid weft thread to insure its entrance between the sets of warps.
15. In a circular loom, the combination with means for manipulating the warp threads and a lay for placing a weft thread in position, of a weaving pin about which the weaving takes place and means for adjusting the weaving pin along the axis of the woven fabric.
16. In a circular loom, the combination with means for manipulating the warp threads and a lay for placing a weft thread in position, of a removable weaving pin about which the weaving takes place and removable pin adjusting means for adapting the loom to covering purposes as well as weaving a tube.
17. In a circular loom, the combination with means for manipulating the warp threads, of means for laying a weft thread and forcing it toward a previously laid weft thread, a weaving pin about which the weaving takes place, and means for adjusting the weaving pin along the axis of the woven tube.
18. In a circular loom, the combination with means for manipulating the warp threads, of a lay provided with a spiral groove for forcing a weft thread toward a previously laid thread, a weaving pin about which the weaving takes place and means for adjusting the weaving pin along the axis of the woven tube.
19. In a circular loom, the combination with means for manipulating the warp threads and a weaving pin about which the weaving takes place, of a lay for placing a weft thread in position and a lay support surrounding the weaving pin and serving to center the pin.
20. In a circular loom, the combination with means for manipulating the warp threads and a core about which the weaving takes place, of a lay curved to conform to the core and provided with a thread guide on its face beginning at a point back from its forward end.
21. In a circular loom, the combination with means for manipulating the warp threads and a core about which the weaving takes place, of a lay and lay holder curved to conform to the core, the forward end of the holder being in advance of the forward end of the lay.
22. In a circular loom, the combination with means for manipulating the warp threads and a core about which the weaving takes place, of interchangeable lays and lay holders curved to conform to cores of different sizes for laying a weft thread in position.
23. In a circular loom, the combination with means for manipulating the warp threads, a core about which the weaving takes place and a lay for placing a weft thread in position, of a lay support on which the lay travels, the said support having its surface toward the lay provided with depressions for holding the warp threads against displacement by the action of the lay.
24. In a circular loom, a central tubular column, provided with an annular ledge on its interior, a weaving pin projecting through the top of the column, a pin supporting rod extending downwardly within the column, a rod guide seated on the said ledge and removable through the top of the column, means for operating the said pin supporting rod and means for manipulating the warp and weft threads to weave around the weaving pin.
25. In a circular loom, a central tubular column, a weaving pin projecting through the top of the column, a pin supporting rod extending downwardly within the column, a horizontal shaft having a rack and pinion connection with the rod and provided with a worm wheel, a vertical shaft provided with a worm in engagement with the said worm wheel for operating the shaft and hence raising and lowering the weaving pin and means for carrying on the weaving operation around the weaving pin.
26. In a circular loom, the combination with a core and means for performing the weaving operation around the core, of a series of evening rolls geared together to operate simultaneously and arranged to deliver the warp threads and a tension device common to all the evening rolls of the series for placing them under the desired tension.
27. In a circular loom, the combination with a core and means for performing the weaving operation around the core, of a series of inter-connected evening rolls for delivering the warp threads and a tension device common to all the evening rolls and arranged to be operated by them.
28. In a circular loom, the combination with a core and means for carrying on the weaving operation around the core, of a series of interconnected evening rolls for delivering the warp threads and a tension roll common to and governing the tension of each evening roll of the series.
29. In a circular loom, the combination with a core and means for carrying on the weaving operation around the core, of an endless series of inter-connected evening rolls for delivering the warp threads, a tension

roll geared to one of the evening rolls and a single screw for regulating the tension.

30. In a circular loom, the combination with a core and means for carrying on the weaving operation around the core, of a series of inter-connected evening rolls for delivering the warp threads, means for applying tension to the series and means for releasing an evening roll without disturbing the other rolls of the series. 70

10 31. In a circular loom, the combination with a core and means for carrying on the weaving operation around the core, of a series of inter-connected evening rolls for delivering the warp threads, and means for applying tension to the series, an evening roll of the series being provided with heads loosely mounted on the roll shaft and with false heads screw-threaded on the shaft for 75 locking the roll to and releasing it from the shaft.

15 32. In a circular loom, the combination with a core and means for carrying on the weaving operation around the core, of a series of inter-connected evening rolls for delivering the warp threads, and a tension roll connected with one of the evening rolls, the said tension roll comprising a series of stationary friction disks, the members of which 80 alternate with the members of a series of rotary disks, a screw-threaded rod extending centrally through the said series, a stop on the rod, a nut coacting with the stop to hold the frictional resistance constant and a second nut on the rod for varying the frictional resistance. 85

25 33. In a circular loom, the combination with a core and means for carrying on the weaving operation around the core, of a series of inter-connected evening rolls for delivering the warp threads and a tension roll connected with one of the evening rolls, the said tension roll including means for adjusting the amount of frictional resistance and 90 means for removing the frictional resistance and reestablishing the same without disturbing the means for adjusting the frictional resistance. 95

30 34. In a circular loom, the combination with a core and means for carrying on the weaving operation around the core, of a tension roll and means for evenly distributing the tension from the tension roll to all the warp threads, the said tension roll comprising an exterior series of friction disks free 100 to move toward and away from one another but connected to rotate together, an interior series of friction disks the members of which alternate with the members of the exterior series, the members of the interior series being free to move toward and away from one another and held against rotation, and means for yieldingly pressing the disks together to increase the rotative resistance of the said 105 outer series. 110

35. In a circular loom, the combination with a core and means for carrying on the weaving operation around the core, of an interconnected series of evening rolls for delivering the warp threads, means for applying tension to the rolls and a ring support for the rolls. 115

16 36. In a circular loom, the combination with a core and means for carrying on the weaving operation around the core, of a series of evening rolls for delivering the warp threads, means for applying tension to the rolls, a ring support for the rolls and means for removably connecting the ring support with the loom frame. 120

18 37. In a circular loom, the combination with the loom frame, a core and means for carrying on the weaving operation around the core, of a series of evening rolls for delivering the warp threads, means for applying tension to the rolls, a ring support for the rolls, removably connected to the loom frame and warp thread guides one for each roll carried by said ring frame. 125

20 38. In a circular loom, the combination with heddles, a shuttle and means for operating them, of means for guiding the warp to the heddles including a plurality of bars for each thread, along which the thread passes and a tilting, spring-actuated arm, one for each thread, provided with eyes through which the thread passes, said eyes on the tilting arm being arranged to alternate with the bars on the guiding means. 130

25 39. In a circular loom, the combination with heddles, a shuttle and means for operating them, of means for guiding the warp to the heddles including a plurality of bars for each thread, along which the thread passes, a tilting, spring-actuated arm, one for each thread, provided with eyes through which the thread passes, said eyes on the tilting arm being arranged to alternate with the bars on the guiding means, and an adjustable bar to which a plurality of arm-actuating springs are attached for simultaneously adjusting the tension of the several springs. 135

30 40. In a circular loom, the combination with a plurality of sets of heddles, a shuttle and means for operating them, of a comb extending continuously along the plurality of sets of heddles for spacing the warp threads after leaving the heddles, the serrations between the comb teeth having their ends toward the head of the comb, where the warp threads rest as the heddles complete their movement, spaced substantially equal distances apart throughout the length of the comb. 140

35 41. In a circular loom, the combination with sets of heddles arranged around a core, a shuttle and means for operating them, of a comb extending around the core and provided with teeth to separate the warp. 145

threads, the serrations between the teeth of the comb having their ends toward the head of the comb spaced substantially equal distances apart throughout the length of the 5 comb, whereby the uniform spacing of the warp threads from consecutive sets of heddles is insured.

42. In a circular loom, the combination with sets of heddles arranged around a core, 10 a shuttle and means for operating them, of an upper and a lower comb extending around the core and having the teeth of one comb directed toward the teeth of the other comb, the said combs having serrations between their teeth oblique to the back of the comb for bringing the ends of the serrations toward the back of the comb at substantially equal distances apart while the opposite ends of the serrations are in position to receive the 20 threads from the different sets of heddles.

43. In a circular loom, the combination with guides or ways arranged in pairs around the weaving point, of heddles mounted in heddle frames provided with bearings 25 adapted to engage and slide along the guides, a heddle frame comprising round side bars and flat cross bars having their ends inserted in the side bars.

44. In a circular loom, the combination with guides or ways arranged in pairs around the weaving point, of heddles mounted in heddle frames provided with bearings adapted to engage and slide along the guides, a heddle frame comprising round 35 side bars provided with screw threads, cross bars having their ends inserted in the side bars, one of said cross bars being movable along the side bars and nuts on the screw-threaded portions of the side bars for adjusting the said movable cross bar to tighten the heddles attached thereto.

45. In a circular loom, the combination with guides or ways arranged in pairs around the weaving point, of heddles provided with loops at their ends, a heddle frame comprising side bars and cross bars, heddle bars passing through the loops in the 45 ends of the heddles and means for removing a heddle bar for replacing heddles.

46. In a circular loom, the combination with guides or ways arranged in pairs around the weaving point, of heddle frames comprising side and end bars, the latter having slide bearings removably secured thereto 50 for engaging the guides or ways and heddle supporting cross bars having their ends removably inserted in the side bars.

47. In a circular loom, a set of heddles comprising two members supported to move 55 simultaneously in opposite directions, a rock shaft provided with oppositely directed arms, links connecting each heddle with one of the arms, and a reciprocating part arranged to rock the said rock shaft back and forth.

48. In a circular loom, a set of heddles comprising two members supported to move simultaneously in opposite directions, a rock shaft provided with arms extending in different directions therefrom and with a pinion, links connecting each of the heddles with one of the arms, a longitudinally reciprocating rack bar engaged with the pinion and means for operating the rack bar. 70

49. In a circular loom, a shuttle driving 75 spindle provided with a shuttle driving pinion and with a bearing roller and a shuttle provided with a curved rack in position to engage the said pinion and with a rim in position to engage the said bearing roller to 80 center the interengaging teeth on the said rack and pinion.

50. In a circular loom, the combination with the core about which the weaving takes place and a shuttle, of a lay carried by the 85 shuttle and a lay support in proximity to the core, the lay being formed to press the warp threads between its edge and the support to supply the necessary tension for weaving. 90

51. In a circular loom, take-off rolls, means for rotating them, rock shafts provided with hangers in which the rolls are mounted and means for simultaneously 95

rocking the shafts to adjust the rolls. 52. In a circular loom, rock shafts geared to rotate together, hangers depending from the rock shafts, take-off rolls mounted in the hangers, a spring lever for operating one of the rock shafts and hence both and means 100 for rotating the rolls.

53. In a circular loom, take-off rolls, means for rotating them, means for setting them at different distances apart and yielding bearings for one of the rolls to permit it 105 to recede from its companion roll when unusual thickness of material enters between the rolls.

54. In a circular loom, take-off rolls, shafts for driving them, and means for connecting their driving shafts with the main driving mechanism of the loom, said means including a worm shaft provided with a hand wheel and a clutch for locking the 110 said worm shaft to and releasing it from the main driving mechanism whereby the take-off rolls may be released from the main driving mechanism and operated by hand at pleasure. 115

55. In a circular loom, the combination 120 with the main drive shaft and a gear wheel for transmitting motion to the take-off rolls, of pinions mounted on the drive shaft to slide along the shaft into and out of engagement with the opposite sides of the said gear 125 wheel whereby the direction of motion of the take-off rolls may remain unchanged when the drive shaft is reversed.

56. In a circular loom, the combination with the drive shaft and a gear wheel for 130

transmitting motion to the take-off rolls, of pinions carried by a sleeve keyed to the shaft in sliding adjustment to bring the pinions into and out of engagement with the 5 opposite sides of the said gear wheel and means for locking the sleeve in its different adjustments.

57. In a circular loom, the combination with a heddle frame way provided with a 10 recess and the bracket for supporting the way, of a lock attached to the bracket and entering the recess in the way.

58. In a circular loom, the combination with heddle-frame ways provided with recesses in their adjacent sides, of an arched 15 spring lock, the ends of which are adapted to enter the said recesses and means for forcing the arched portion of the lock toward the brackets to cause the lock to 20 press laterally against the ways.

59. In a circular loom, a central, hollow column, a portion of which is composed solely of the superposed hubs of revolving

parts, whereby access may be had to surrounding parts of the loom from within the 25 central hollow column.

60. In a circular loom, a base provided with a tubular step, a cam wheel having a hollow hub and a tubular extension bolted thereto and seated in said step, a master 30 gear wheel having a tubular hub and bolted to the hub of the cam wheel and means for centering the hub of the gear wheel.

61. In a circular loom, a cam wheel normally located with its hub in the vertical 35 central axis of the loom, the said cam wheel being removable from the loom without disturbing the loom frame.

In testimony that I claim the foregoing as my invention I have signed my name in 40 presence of two witnesses this thirteenth day of December, 1911.

VERNON ROYLE.
